US00D748702S

(12) **United States Design Patent**
Velozny

(10) **Patent No.:** **US D748,702 S**
(45) **Date of Patent:** **** Feb. 2, 2016**

(54) **ACCESSORY FOR INNER RING OF DRILLING CUP AND FOR HOUSING OF ELECTRICAL APPLIANCES**

(71) Applicant: **Nir Velozny**, Tel Aviv (IL)

(72) Inventor: **Nir Velozny**, Tel Aviv (IL)

(**) Term: **14 Years**

(21) Appl. No.: **29/491,852**

(22) Filed: **May 27, 2014**

(30) **Foreign Application Priority Data**

Nov. 27, 2013 (IL) 54823

CLAIM

The ornamental design for an accessory for inner ring of drilling cup and for housing of electrical appliances, as shown.

DESCRIPTION

FIG. 1 is a top view of an accessory for inner ring of drilling cup and for housing of electrical appliances showing my new design;

FIG. 2 is a bottom view thereof;

FIG. 3 is a front view thereof;

FIG. 4 is a back view thereof;

FIG. 5 is a right view thereof;

FIG. 6 is a left view thereof;

FIG. 7 is a perspective view thereof; and,

FIG. 8 is a perspective view thereof.
